UNITED STATES PATENT OFFICE.

ARTHUR G. ROGERS, OF MERIDEN, CONNECTICUT, ASSIGNOR TO THE
C. ROGERS & BROS. OF MERIDEN, CONN., OF SAME PLACE.

DESIGN FOR A HANDLE FOR SPOONS, &c.

SPECIFICATION forming part of Design No. 31,116, dated July 4, 1899.

Application filed June 9, 1899. Serial No. 719,977. Term of patent 7 years.

To all whom it may concern:

Be it known that I, ARTHUR G. ROGERS, of Meriden, in the county of New Haven and State of Connecticut, have invented and produced a new Design for a Handle for Spoons, Forks, Knives, and Similar Articles; and I do hereby declare the following, when taken in connection with the accompanying drawing and the letters of reference marked thereon, to be a full, clear, and exact description of the same, and which said drawing constitutes part of this specification and represents a face view of a handle embodying my design.

This invention relates to a design for a handle for spoons, forks, knives, and similar articles; and it consists in the design as hereinafter described and shown in the accompanying illustration.

The general outline of the handle is similar to that of the "fiddle-back" pattern, and the face is ornamented by long scrolls A, extend-

ing from the inner end of the shank upward, the said scrolls starting in foliated scrolls B and merging into foliated scrolls C near the center of the handle. The main portion of the upper end of the handle is plain, forming an elliptical panel D, which is contracted at its ends, the lower end merging into the foliated scrolls C, and on each side are floral scrolls E, which are elaborated at the upper end, terminating in an ornamental tip F.

I claim—

The design for a handle for spoons, forks, knives and similar articles as herein shown and described.

In testimony whereof I have signed this specification in the presence of two subscribing witnesses.

ARTHUR G. ROGERS.
